UNITED STATES PATENT OFFICE

FREDRIK WILLE, OF CHICAGO, ILLINOIS

FURNACE FOR TREATING SHEET METAL OR THE LIKE

Application filed May 4, 1927. Serial No. 188,676.

This invention relates to conveyor mechanism more particularly to conveyors adapted to be operated in connection with furnaces of the tunnel type for conducting material to be heated through the heating chamber of the furnace.

It is among the objects of the invention to provide a conveyor-mechanism especially applicable for use in furnaces for heating or 10 heat treating sheet metal such as tin-plate, strip or the like, without subjecting the material to any engagement with the movable elements of the conveyor mechanism or the stationary element of the furnace while being transferred therein.

Another object of the invention is to provide a conveyor mechanism especially adapted for use in furnaces in which the conveyor element is disposed in the heating chamber 20 of the furnace in a manner to cooperate with the stationary hearth and in which the actuating mechanism for the conveyor is disposed outside of the furnace to protect it from the intense heat of the furnace chamber.

Another object of the invention is to provide a combined conveyor mechanism and furnace structure of the above designated character which will be of simple, compact, and durable mechanical construction, which 30 shall be efficient in its operation, and which shall be adapted to transfer work in the furnace without effecting relative movement of the work with the portion of the furnace and conveyor-mechanism with which it is engaged while passing through the furnace.

Various forms of conveyor mechanism have been heretofore proposed for conducting work through a furnace and of these the movable hearth furnace is one most commonly 40 used. In this type of furnace the hearth operates as an endless conveyor and its construction does not lend itself to a design of furnace which is efficient in its application of heat to the work to be acted upon.

In accordance with the present invention these difficulties are overcome by providing a conveyor mechanism which extends the full length of the furnace and co-operates with the hearth to transfer the material on the latter. The carrier element of the conveyor

which engages the work to transfer it on the hearth is adapted to raise the work from the hearth, advance the same in a lateral direction and then return to its original position to again engage the work at another portion of its surface whereby it is transferred in successive steps from one end of the hearth to the other.

In the accompanying drawings constituting a part hereof and in which like reference characters designate like parts, Fig. 1 is a vertical sectional view partially in elevation of a combined furnace and conveyor mechanism embodying the principles of this invention; Fig. 2 is a top plan view thereof with the roof of the furnace and the arch of the heating chamber removed; Fig. 3 is a side elevation view; Fig. 4 detail views in side elevation of the cam mechanism illustrating the relative position of the cams and cam followers during a complete operating cycle of the cams; Fig. 5 is a plan and side elevation view of work supporting links mounted on the transverse bars of the conveyor mechanism to more clearly illustrate their manner of mounting; and Figs. 6, 7 and 8 are an enlarged sectional elevation, side elevation and plan view, respectively, of a portion of the furnace and conveyor mechanism.

Referring to Fig. 1 of the drawings the structure therein illustrated comprises side walls 1, a roof 2, a transverse arched section 3 and an arched section 4 of a furnace. The section 3 constitutes the furnace hearth and divides the lower combustion chamber 5 from the heating chamber 6 and the chamber 7 between the roof and arch 2 and 4 respectively constitutes a by-pass for preheating air that is conducted to the combustion chamber 5.

As shown in Fig. 2 the combustion chamber of the furnace extends from one end underneath substantially one-half of the furnace hearth and communicates with the heating chamber 6 through a plurality of conduits 8 which are disposed along the side walls as shown in Fig. 2. Mounted on the hearth 3 are a plurality of projecting lugs 9 on which the work such as tin-plate or strip is supported when at rest on the furnace hearth. Lugs 9 are in suitably spaced rela-

tion, as shown, to adapt them for cooperation with the carrier element of the conveyor which consists of the following mechanism:

Referring to Fig. 3 of the drawings a pair of longitudinal side frames 10 are provided with transverse bars 11 which are secured to the side frames by suitable clamping brackets 12. The bars 11 project through openings 13 provided in the side walls 1 of the furnace 10 and are adapted for bodily movement therein in a manner hereinafter stated. The bars 11 are provided with cover plates 14 of such dimensions as to adequately cover the openings 13 for any position of the bar therein 15 and the plates 14 are in intimate engagement with side plates 15 provided on the outer walls of the furnace to seal the heating chamber against the loss of heat. As shown in Fig. 1 the bars 11 may be tubular members 20 connected at their respective ends to a cooling medium such as water or an air blower to maintain the bars 11 at a suitable temperature within the heating chamber.

The side frame portions 10 of the carrier 25 member are provided with flange wheels 16 which are mounted on rails 17 of a supporting frame structure 18 and the latter is provided with rollers 19 which constitute followers for a plurality of cams 20. The frames 30 18 are movable on guides 21, Figs. 3 and 7. As shown in Figs. 1 and 3 the carrier frames 10 are provided with angle brackets 22 which are secured to the webs of the outer channel frame sections and which are adapted to be 35 engaged by rollers 23 mounted on levers 24 and 25. The levers are pivotally mounted at 26 and 27 to bearing brackets 28. The lower ends of the levers 24 and 25 are provided with rollers or cam followers 29 and 30 which engage a pair of cams 31 and 32 mounted co-axially with the cams 20 on shafts 33 which are journalled in pedestal bearings 28.

The cam mechanism is operated through a worm gear mechanism or any suitable gear reduction contained in the housings 35 which are operatively connected to a drive motor 36 through shafts 37 as shown in Fig. 3. The motor 36 drives the shafts 33 which rotate the cams to actuate the carrier mechanism in 45 the following manner: As shown in Fig. 4 the cams 20 and 31 are disposed in opposed relation 180 degrees apart so that when the cam followers or rollers 19 which are journalled in the track frames 18 are in their elevated position the follower 29 of the lever which contacts with the carrier member is on the low portion of its cam 31. This phased relation of the cams and rollers is maintained for a purpose as will be set forth in connection with the description of the operation of 55 the conveyor mechanism.

A series of links or bars 40 having undercut seat portions 41 are adapted to engage the transverse bars 11 of the carrier as shown 60 in Fig. 5. The bars 11 are provided with

collars or shoulders 42 to maintain the members 40 in suitably spaced relation corresponding to the spacing of the projecting lugs 9 of the furnace hearth. This is shown in Fig. 2 in which the transverse bars are 70 illustrated as movable between double rows of projections 9 and the links 40 are disposed longitudinally between the lugs 9 so as to clear the latter in their movement when the carrier-mechanism is actuated. The links 40 are provided with projections 43 which 75 constitute points of contact or seats for engaging the material 45, Figs. 1 and 6 conveyed through the furnace.

The operation of the conveyor mechanism is briefly as follows: When the motor 36 is energized, shafts 33, on which cams 20 and 31 are mounted, are actuated, to rotate through the reduction gear mechanism 35 and the supporting track structure 18, and the laterally movable carrier mechanism comprising, side frames 10 and the transverse bars 11 with connecting links 40, is movable through the cam-mechanism to transfer the work on the supports 9 of the hearth in the 80 following manner:

The cam elements 20 and 31 are designed to lift the rollers 19 of the track frame 18 and maintain the latter in elevated position during 90 degrees of its travel and the cam which actuates the lever 24 of the side frames 10 is ineffective in producing movement of the lever 24 during the period in which the roller 19 is rising on the cam. This relation of the cam and rollers is shown in position 95 1 of Fig. 4 and in position 2 the roller 19 and the track support 18 in which it is journalled have been elevated to their uppermost position which is illustrated by the bar 11 being disposed in the upper left hand corner of the rectangular figure shown in dotted lines to indicate its path of movement. When the roller 19 has reached its elevated position, the cam 31 is in position 2 of Fig. 4 which is the position at which the roller 29 of the lever 24 is contacting with the gradually rising portion of the cam 31 and as the high point of the latter approaches the position of roller 29 the lever 24 is subjected to angular movement on its pivot 26 causing a lateral displacement of the carrier frame 10 to the right when viewing the structure of Fig. 3 from the right hand side of the sheet and the carrier will then be in position 3 of Fig. 4. In this position the roller 19 of the track frame is approaching the fall of the cam 20 and further rotation of the latter will cause the track 18 to be lowered to position 4 without disturbing the lateral position of the carrier frame 10. When the track frame 18 has been lowered, cam 31 will be as shown in position 4 of Fig. 4 in which the roller 29 of the lever 24 upon further rotation of cam 31 will move 100 radially inward on the cam and recede from 105 the latter. The cam 20 is then rotated to 110 position 5 in which the roller 29 of the lever 24 is contacting with the high point of the cam 20 and the track frame 18 is then rotated to position 6 in which the roller 19 is journalled in the track support 18. The cam 20 is then rotated to 115 position 7 in which the roller 29 of the lever 24 is contacting with the fall of the cam 20 and the track frame 18 is then rotated to position 8 in which the roller 19 is journalled in the track support 18. The cam 20 is then rotated to 120 position 9 in which the roller 29 of the lever 24 is contacting with the high point of the cam 20 and the track frame 18 is then rotated to position 10 in which the roller 19 is journalled in the track support 18. The cam 20 is then rotated to 125 position 11 in which the roller 29 of the lever 24 is contacting with the fall of the cam 20 and the track frame 18 is then rotated to position 12 in which the roller 19 is journalled in the track support 18. The cam 20 is then rotated to 130 position 13 in which the roller 29 of the lever 24 is contacting with the high point of the cam 20 and the track frame 18 is then rotated to position 14 in which the roller 19 is journalled in the track support 18.

the angle bracket 22 whereby the carrier frame 10 is free to be moved laterally in a left hand direction and this movement is effected through the cam at the extreme right 5 of Fig. 3, which is opposed to cam 31 on the left of the figure. When the cam mechanism that controls lever 24 is in position 4 of Fig. 4 the cam which actuates lever 25 will be in the position in which the roller 30 will rise 10 on its cam to displace the lever above its pivot 27 to produce lateral movement of the carrier frame 10 to the left which is its initial position 1.

The operation as described constitutes a 15 complete operating cycle which involves raising the track structure 18 moving the carrier frame laterally in one direction while maintaining the track structure in its raised position, lowering the track structure while 20 maintaining the carrier in its laterally displaced position and returning the carrier to its original position while the track structure is maintained in its lowermost position. This cycle of operation is 25 repeated to successively raise and lower the track structure and laterally move the carrier mechanism in opposite directions within the limits of its lateral travel.

The openings 13 in the side walls of the 30 furnace are of such dimensions as to permit unimpeded movement of the conveyor bars 11 as previously explained, and the bars 11 traverse a rectangular path as shown in dotted lines in Fig. 4. The work is moved 35 through the furnace by the conveyor mechanism in the following manner:

When the track support and carrier frames 10 and 18 are raised by the cam, the work, such as rolled sheets or strip, is raised from the supporting lugs 9 of the hearth; when 40 the carrier is subsequently moved laterally to the right the work is carried with it and when the carrier frame is subsequently lowered by the cam the work is deposited on the hearth lugs 9. The operating cycle of the 45 carrier is continuous for the purpose of moving the work through the entire length of the furnace. From a study of the conveyor mechanism and its cooperative relation with the furnace hearth, or the stationary supports 9, it is evident that at no time during the 50 raising and shifting of the work or during the transfer of the work from one position to another on the furnace hearth will there be relative movement between the work and the elements with which it is brought in contact, namely, the supporting links 40 of the, 55 transverse bars 11 of the carrier or the stationary lugs 9 of the hearth. This feature 60 is the basis on which the principle of the conveyor mechanism is predicated and its object is to prevent a marring or scratching of tin plate or other sheet material that is passed through the furnace.

65 In other forms of mechanism heretofore

proposed the work and its carrier mechanism such as rollers or other movable elements were subjected to relative movement which marred the surface of the material resulting in a loss in their commercial value as sheets so marred are considered seconds in the trade.

70 Although the invention has been illustrated as embodied in a furnace for moving material through a furnace, it is to be understood that the conveyor mechanism is applicable for use anywhere and for any purpose where it is desired to convey or transfer materials in the manner specified. It is further evident that various modifications 75 may be made in the details of construction and in the arrangement of the several cooperating parts without departing from the principles herein set forth.

80 I claim herein as my invention:

1. A conveyor mechanism comprising in combination a plurality of work supports, a work carrier cooperating with said supports to transfer the work thereon, a track support for said carrier, a plurality of cams in cooperative engagement with said track support, and a plurality of cams cooperatively engaged with said carrier, said track and carrier operating cams being mounted for rotation on common drive shafts with their 85 extended faces in opposed relation to successively raise said track, move the carrier thereon in one direction, lower the track, and return the carrier to its initial position on the track.

90 2. In a heating furnace the combination with a hearth of a work carrier adapted to transfer the work thereon, and cam mechanism for actuating said carrier to raise the work from the hearth, move it laterally while in its raised position and lower the same to the hearth, without producing relative movement of the work and hearth or the work and carrier while the work is in engagement with the one or the other, said carrier being partially disposed within the heating chamber of the furnace and projecting through the walls thereof and said cam mechanism being disposed on the outside of the furnace and in cooperative engagement with the outwardly 95 projected portion of said carrier.

100 3. In a heating chamber the combination with a hearth of a work carrier adapted to transfer the work thereon comprising a track support, a plurality of side frames mounted for lateral movement on said support, a plurality of supporting bars disposed transversely of said frame and secured thereto and projecting through openings in said furnace walls, closure plates mounted on said bars and movable therewith to seal the openings through which the bars project, and cam mechanism for successively raising said track support, subjecting the side frames to lateral movement thereon in one direction while in 105 110 115 120 125 130

its raised position, lower the supports and return the side frame members to their initial position on the track support to advance the work through the heating chamber of the furnace in successive steps.

5 In testimony whereof, I have hereunto set my hand.

FREDRIK WILLE.
